Fig. 8.

Fig. 9.

Fig. 10.

FIG. 11.

FIG. 1 is a side elevational view of a cart showing my new design;

FIG. 2 is an end elevational view thereof;

FIG. 3 is a top plan view thereof;

FIG. 4 is a perspective view thereof with the shelves in extended position;

FIG. 5 is a perspective view of a modified form of the cart shown in FIG. 1;

FIG. 6 is a perspective view thereof with the shelves in extended position;

FIG. 7 is a perspective view of another modified form of the cart shown in FIG. 1, but with the shelves in extended position;

FIG. 8 is a perspective view of another modified form of the cart shown in FIG. 1;

FIG. 9 is a perspective view thereof with the shelves in extended position;

FIG. 10 is a perspective view of another modified form of the cart shown in FIG. 1; and

FIG. 11 is a perspective view of another modified form of the cart shown in FIG. 1.

This application is a continuation application of my copending applications Serial No. D. 66,080, filed July 26, 1961, Serial No. D. 66,078, filed July 26, 1961, and Serial No. D. 66,379, filed August 16, 1961 and now abandoned.

I claim:

The ornamental design for a cart, as shown and described.
